SOUND RECORDING AND REPRODUCING
MACHINE

Edward Robert Harris, Los Angeles, Calif.

Application June 10, 1940, Serial No. 339,751

6 Claims. (Cl. 274—9)

My invention relates to sound recording and reproducing machines wherein the records are made on disks, flat strips or cylinders of material wherein the sound record is made by a stylus excavating a sound groove in the material of a record holding body.

The constructions here shown are applied to a disk record body. Certain functional units of mechanism, relating chiefly to the stylus mounting herein shown, can be adapted to be used on flat strip record bodies and also on cylindrical bodies.

An object of my invention is to provide a compact, portable unit complete in itself which is adapted to record and reproduce and to play back the standard, commonly used form of sound records of the disk type, known as variable, rotational speed records, useable with the ordinary phonographs which are out in service.

In addition to what is set forth above a further object of my invention is to provide means for making and using disk sound records wherein the sound groove is uniform as to the length of speed of travel of the sound groove under the stylus on any portion of the record body.

With the common disk record the sound groove travel under the stylus is much faster at the margin of the disk than at the central small diameter of the record.

With my invention there is mechanism for producing a differential rotary speed imparted to the turn table so that an equal lineal length of sound groove of disk travel under the stylus, meaning a uniform rate of speed travel of the stylus on the record, is maintained throughout the record. In this manner there is made a sound groove which will produce the best reproduction of sound with the least length of groove, permitting a longer time record of sound on a given diameter record than by the old form of constant uniform revolution speed of the disk.

A prime object of my invention is to provide a highly efficient, light weight, simple and low cost instrument which may be used successfully by any one, being as nearly as possible a fool proof instrument.

A further object of my invention is to provide mechanism which may be easily and quickly adjusted to play back either of the above described types of sound groove records as relates to disk records and to do this without changes which require any special tools.

A further object of my invention is to provide special electrical mechanisms for rotating the turn table on which the record disks are carried.

Another object of my invention is to provide a special efficient recording and play back stylus holding mechanisms which are adapted to produce and play back sound grooves of the highest quality.

Another object of my invention is to provide suitable and efficient frictional driving mechanisms for revolving the turn table on which the record disks are carried.

5 Other objects of my invention will appear from the detailed descriptions herein shown.

Reference will be had to the accompanying drawings in which

Fig. 1 is a plan across below the turn table on line 1—1 of Fig. 6 with parts broken away for clearness of illustration.

Fig. 1a shows a wiring diagram of the electrical conductor wiring as relates to the wiring from the stylus head.

15 Fig. 1b is a plan of the rocker frame member or carriage on which the mechanisms for revolving the turn table are carried.

Fig. 2 is an elevation partly in section on line 2—2 of Fig. 1.

20 Fig. 3 is an elevation on line 3—3 of Fig. 1 showing details of gearing.

Fig. 4 is a sectional elevation on line 4—4 of Fig. 1.

25 Fig. 2a is a sectional elevation on line 2a—2a of Fig. 1.

Fig. 5 is a sectional elevation on line 5—5 of Fig. 1.

Fig. 6 is a sectional elevation on line 6—6 of Fig. 1.

30 Fig. 7 is a sectional elevational detail on line 7—7 of Fig. 5.

Fig. 8 is a sectional elevational detail on line 8—8 of Fig. 6.

Fig. 9 is a plan sectional detail on line 9—9 of Fig. 6.

35 Fig. 10 is a longitudinal, vertical, central, partially sectional elevation through the stylus holding mechanisms.

Fig. 11 is a plan of what is shown in Fig. 10 with the enclosure box and parts in section.

40 Fig. 12 is a vertical section on line 12—12 of Fig. 10.

Fig. 13 is a left end view looking from the left toward the right of Figs. 10 and 11 with parts broken away.

45 Fig. 14 is a left side elevation of the machine.

Fig. 15 is a front elevation of the machine.

In the drawings a disk record D is indicated in outline by dotted lines in Fig. 1. In Fig. 6 the disk is shown as a central portion in vertical section. The disk is supported on a turn table T of suitable diameter in relation to the disk which it supports.

The turn table T is mounted on a tubular 55 shaft 2 and is fixed to this shaft through the medium of a separate hub 126 having a flange 127 fastened by screws to the disk, see Fig. 6. This hub 126 is secured to the shaft 2 in any suitable manner and is here shown by a set screw 3. On shaft 2 there is a collar 4 over which the central

60

aperture of disk D is mounted. The tubular shaft 2 is supported within a tubular post 5. On top of this post 5 there is a spacer collar 6 which may be used in slightly different thicknesses for adjustment purposes.

The post 5 is provided at its lower end with a lug 7 which is fastened by a bolt 8 to a block 9 fixed on a cross bar 10 on the baseboard 11 which forms the general base of the machine. On the inside of the shaft 2 there is a shaft 12 which is connected to revolve with shaft 2 by means of a pin 13 fixed in shaft 12 and with its end extending into an aperture 14 in shaft 2. On the bottom shaft 12 there is loosely mounted a small gear 15 normally running as an idler on shaft 12 and held onto shaft 12 by a small collar 17 on the end of shaft 12.

On the top of shaft 12 there is mounted a screw cap 16 by suitable threads. When cap 16 is screwed down tightly it lifts shaft 12, thus drawing the gear 15 up tightly to the end of shaft 2 in frictional contact to cause the gear 15 to rotate with the shaft 2 actuated by turn table T and also clamping disk D on the table by the cap 16.

When screw cap 16 is not clamped tightly down then the gear 15 runs on an idler on shaft 12. This idler situation of gear 15 occurs only when the machine is used for playing back old style records in which a constant revolutionary speed of the turn table is maintained.

When the machine is used for disk records recording or reproducing uniform sound groove distances being uniform rate of travel speed of the stylus on the record sound groove, the gear 15 is clamped tightly by the screw cap 16 to revolve as a unit with the turn table T.

The gear shaft 12 with its gear 15 drives a horizontal transverse screw threaded shaft 18 by any suitable means which is here shown as being composed by a gear 19 which is mounted on a short vertical shaft 20 on which there is also mounted a worm gear 21 which engages and drives a gear 22 on the aforementioned threaded shaft 18. The vertical shaft 20 is mounted at its bottom end in a bearing in or on the cross bar 10. The top of shaft 20 is supported by a bracket 23. The threaded shaft is mounted at its ends in bearings on posts 24 and 25.

The turn table T is revolved by a friction wheel 26 which contacts the under side of the table 27. This wheel 26 is provided on its outside with a long hub 28, see Fig. 1, mounted to revolve on a stud shaft 29 fixed in a motor frame 31. On the inside of friction wheel 26 there is fixed on its inside hub a gear 30, see Fig. 3, which revolves with wheel 26. An idle gear 32 is mounted on a stud 33 fixed to the motor frame 31 and is engaged by a gear 30 which in turn engages a pinion 33 mounted on a shaft 34 also fixed into the motor frame 31. Pinion 33 is connected to the hub of a friction wheel 35 and revolves with it on a shaft 34, see Figs. 1, 2 and 2a, and is engaged and driven by a friction pinion 38 on an electric motor shaft 39. In place of friction pinion 38 driving wheel 35 I may substitute a suitable gearing therefor as desired.

The friction service of friction pinion 38 with the friction service of wheel 35 are normally intended to wear sufficiently as not require renewal of those surfaces. However when desired I change the diameter of the wheel 35 or its mountings which support the wheel 35 to swing around on a radius of the stud 33 and thus

provide that the wheel 35 be adjusted to the pinion 38 to take up wear of those friction surfaces without having to renew the parts.

A suitable electric motor for driving the aforesaid gearing is indicated by 40 which is mounted in a suitable motor frame 31 by means of self aligning bearings 41.

The motor frame 31 is provided with stud projections 37 on the inside of the frame and over which there are tubular rubber bushings 37a on which are mounted bearings 42 of a rocker frame carriage member 45 which is shown in plan in Fig. 1b. The bearings 42 are on studs 44 on carriage 45 and these studs have bearing seats 43 in which are carried the rubber bushings 37a, which are to prevent the transmission of vibratory motion to the frame of the machine and also acts as a rotatable cushion permitting a small amount of up and down movement of drive wheel 26 and connected motor frame work, thereby absorbing any small variation in the plane of rotation of the turn table. This feature of self adjustment by the rubber tube bushings is highly important in accommodating the revolving parts to automatically balance to their own centers and thereby preventing vibrations of the parts.

The motor frame 31 carries as a unit the aforementioned gear driving train which drives the friction wheel 26 which drives by frictional contact the under surface 27 of turn table T. A spring 46 connected at the top of motor frame 31 and extending down and connected to rocker frame carriage 45 holds the friction wheel 26 always in elastic contact with the bottom surface 27 of turn table T by a rocking motion of motor frame 31 about the bearings 42 on the studs 44 of rocker frame carriage 45.

This carriage 45 is mounted at 47 to rock and slide along a transverse shaft 48 which is supported by angle blocks 49 on the base 11 of the machine. The carriage 45 is provided with an extension end 50 broken away in Fig. 1 and integral in Fig. 2. On this end 50 there is fixed a pin 51 on which is mounted a spring 52, see Fig. 2, which spring is connected by an arm 53 fixed on a cross bar 54. This bar 54 is mounted to rock and slide along a shaft 55 fixed at its ends by angle brackets 56 which are mounted on a cross block 57 on the base board 11.

The rocking, tilting and transverse movement of rocker frame carriage 45 on shaft 48 acts also to rock and move transversely the cross bar 54 on its supporting shaft 55 through the medium of spring 52 and arm 53.

On cross bar 54 there is fixed the upright tubular post 58 over which there is mounted a tubular post 59 a set screw 62 on post 59 clamps it against rotation or allows it to rotate as desired. The post 59 carries the tubular arm 60 on which stylus head 61 is mounted.

The weight of the front end of carriage 45 together with the weight of the motor 40 located on this end of the carriage 45 which are on the front side of shaft 48 shown on the left side of shaft 48 in Fig. 2 always prevents the stylus head from falling on the turn table when the motor drive does not contact the turn table and is inactive as to rotating the turn table. Thus the stylus head is held up elastically by the spring 52 on stub pin 51 on the extending end 50 of carriage 45, the spring 52 contacting the arm 53 is fixed to cross bar 54 which supports the stylus head.

On bar 54 there is fixed a plate 63 on which

there is fixed a counterbalancing spring 64, see Fig. 7. This spring 64 in service contacts a cross rod 65, being a part of a crank shaft 91, to counterbalance in part the weight of the weight of the arm 60 and stylus head 61 from pressing down on the sound grooves of the records. This counterbalancing spring 64 is used only when records are played back and not in cutting new sound tracks.

On rocker frame carriage 45 on its portion 47 there is fixed a Z bar 66 on which is fixed a threaded half nut 67 adapted to be engaged by the threads of shaft 18 when contacted by a rocking motion of carriage 45.

The rocking motion of carriage 45 on shaft 48 is produced through the mechanism of a roller 68 on a pin 69 fixed into the carriage frame 45 together with a flat bar 70 on which the roller 68 is always in contact, which contact is produced by the weight of this end of the carriage 45 and the weight thereon of the motor 40 and its frame 31. These always keep the roller 68 in contact with the flat bar 70.

While the roller 68 is a desirable construction, depending somewhat, as relates to the roller alone in relation to the load on these parts, as when the load is light it may be carried by the pin 69 alone or by a suitable substitute for the pin in the form of a projection on the end portion of the carriage 45 or the end of the carriage itself.

The flat bar 70 is mounted at its ends in trunnions 71 at the left and 72 on the right. For the purposes herein shown I prefer to use the flat bar 70 mentioned, which is of simple construction and is intended to mean wherever used herein, to cover equivalent constructions of eccentric form. These trunnions are mounted in angle brackets 73 fixed to the frame base 11. On trunnion 72 there is mounted a gear 74 which meshes with a gear 75 mounted on an upright shaft 76, on top of which there is a hand hold knob 77.

By turning knob 77 in either direction the flat bar 70 may be made to revolve ninety degrees from the flat position shown in Figs. 1, 2 and 4 to an upright, vertical position shown in Figs. 14 and 15 which then raises roller 68 from position of full lines to the dotted position shown in Fig. 4.

The flat position of bar 70 in Figs. 1, 2, 4 and 6 is that in which the half nut 67 is free from contact with threaded shaft 18. In this position the carriage 45 is free to slide laterally or crosswise of the machine along the shaft 48.

When flat bar 70 is set on edge, see Figs. 14 and 15, then the half nut 67 contacts the threaded shaft 18. This results in locking carriage 45 to be moved laterally or crosswise only by the revolving of shaft 18. This lateral or crosswise movement of 45 by shaft 18 is produced only when the cap nut 16 is screwed down as previously described when gear 15 is clamped to revolve with shaft 12 and it by the revolving of turn table T.

When gear 15 is not clamped to shaft 12 then the half nut 67 locks the carriage 45 from lateral movement at all times when flat bar 70 is on edge in contact with roller 68. This is the situation only when ordinary sound groove records are played back with the machine.

The free lateral movement of carriage 45 along the shaft 48 when the carriage is not locked as described, may be actuated by revolving the hand hold knob 77 on a vertical shaft 78 suitably

mounted and carrying a small gear 80 which engages a larger gear 81 mounted on the vertical portion of a crank arm 82, see Fig. 1, which is connected to a link 83 on a pin 84 on the carriage member 45, whereby the knob 78 will move carriage 45 laterally and carry with it the motor drive 40 which revolves the turn table T and also the bar 54 on which the stylus arm post 59 is mounted.

The lateral movement of carriage 45 produced by the revolution of the threaded shaft 18 is the situation when the machine is used to record and play back the sound groove of equal units of length.

When common or constant rotational speed records are played then the carriage 45 is locked against lateral movement as previously described.

The vertical shaft 79 and crank arm 82 are supported to base 11 by the plate 85 supported on a block secured to the plate 87 on base 11, see Fig. 4.

The vertical shaft 78 is mounted at its bottom in bearing 128 fixed to base 11, see Fig. 4 and Fig. 15. At the upper ends the vertical shafts 78 and 79 are supported in any suitable manner and here are shown as supported in a cross beam 129 suitably fixed to the enclosure box in which the machine is mounted for service. This box is not shown in these drawings.

On trunnion 71 of flat bar 70 there is mounted a crank arm 88 to which is attached a rod 89. On the other end of rod 89 it is connected to a crank arm 90 mounted on a crank shaft 91. This shaft has an offset rod portion 65 and is mounted in brackets 92 on the base 11.

When knob 77 is revolved reverse clockwise the inside edge of flat bar 70 is revolved to become the top of the bar in contact with the roller 68. This movement swings crank arm 88 to push rod 89 to swing arm 90 to revolve the shaft 91 as indicated in Figs. 5, 7, 14 and 15. This brings the rod portion 65 of shaft 91 to contact the spring 64 and thereby act as a counterbalance as before mentioned. When knob 77 is revolved clockwise it causes the flat bar 70 to move its front edge to the top in contact with roller 68 and causes a reverse movement of shaft 91 by a right swing of the arms 88 and rod 89. This movement of shaft 91 causes the rod portion 65 to fall away downward in relation to counterbalancing spring 64 to relieve its pressure in counterbalancing of stylus arm 60 and head 61 to allow the stylus more weight to act in recording contact with a record on turn table T.

An electrical switch 93 of any suitable construction is provided, see Figs. 1 and 5, having a central pin or axis 94 about which contact arms 95 and 96 are mounted and switch shifting the electrical current flow as indicated by the diagram in Fig. 1a, in which these contact arms are shown closing the electric circuit C, thus putting a microphone in service to actuate the recording stylus to make a recording sound. When the arms 95 and 96 are switched over to contacts 98 and 97 this puts in service the circuit E which then becomes the electric circuit from the reproducing stylus head to the loud speaker.

While the electric switch may be of any suitable form I prefer a rotary type 93 mounted on a center pin 94, see Figs. 1, 2 and 5 having an actuating pin 99 which is contacted by pins 100 on a block 101 on shaft 91 which has the rod portion 65. This shaft 91 when moved by the counterclockwise movement of knob 77 actu-

ates the switch 93 to break the circuit C and to close the circuit E. Pins 100 in their rocking movements contact actuating pin 99 of the switch. On the clockwise movement of knob 17 the electric switch closes the circuit C as shown in Fig. 1a.

The electric motor 40 may be provided with any suitable speed governor, and is here shown as a ball governor 102 on motor shaft 39, and is provided with a friction disk 103 fixed to the shaft which the governor acts to draw away from the motor frame 31 to contact a friction arm 104 on the motor frame 31. Lead wires 105 extend from the motor 40 to a suitable electric power supply.

The stylus head 61, see Figs. 10 to 13 inclusive, is provided with a stylus point 106 mounted in a radius block 107, and secured therein by a set screw 108. The radius block 107 is fixed to a stylus shaft 109 which is carried in bearings 110 and 111. These bearings are split on one side through which there passes the clamping screws 112. This provides means for holding the shaft in these bearings preventing chatter of the shaft. At the right end of shaft 109 there is fixed a flat link 113 which is secured at its right end to a block 114. Thus, there is prevented endwise movement of shaft 109. On stylus shaft 109 there is fixed a cross vibrator armature block 115 having its ends extending through the central regions of magnet coils 116 and 117 located over the stylus shaft 109 and around which coils there are mounted magnet blocks having vertical portions 118 and transverse top and bottom ends 119 extending over at the top and bottom of the coils.

Screw bolts 120 fasten these magnet blocks to the bottom of the housing enclosure of the head.

The magnet blocks 118 are connected by the ends of a horse shoe magnet 121. A transverse block 122 of nonmagnetic metal is mounted on the top of the magnet blocks and coils by the screw bolts 120. This transverse block 122 is slotted across its width in which slot there extends the upper end of vibrator block 115. The upper end of block 115 is connected on each side by rubber tip ends of adjusting screws 123. These screws provide accurate means for controlling the vibrations of stylus shaft 109. The rubber tip of one screw 123 is slightly softer than its opposite tip to act as a sort of dampering action of the vibration of block 115. These screws may be adjusted for any desired clearance between them and the armature block 115.

Suitable electric wires 124 extend from the coils 116 and 117 through the tubular arm 68 to and through the tubular post 58 and to the switch 93, for service in relation to the electrical actions involved with the stylus 108. A sufficient amount of slack conductor wire extends from the bottom of post 58 over to the switch 93 to allow for the transverse movement of the stylus across the machine. Suitable wires 125 extend from motor 40 to carry the electric current thereto.

A very important feature of my invention is the fact, that while sound recording and reproduction of a very high quality can be produced by the machine herein described, a very high degree of efficiency at a very low cost is also easily obtainable, resulting in a most inviting sales position.

A special feature of low cost and high efficiency is the mounting of the turn table T on a separate hub 126 having the flange 127 suitably fixed to the shaft 2. This is performed by providing the shaft 2 as a unit, then applying and securing to the shaft by any suitable means, a hub 126 hav-

ing a flange 127, then turning for facing this flange, while fixed to the shaft, to accurate relationship with the shaft. When this is done and the disk turn table T is truly machined it is then mounted on the flange 127 by any suitable means and is here shown fixed by screws. This construction obviates slight variations that are impossible to avoid in fitting shafts to hubs of turn tables T in place of hubs which are an integral part of the turn tables. Even slight variations in these parts result in objectional vibrations in service of this type of machinery.

The rubber bushings 31a on which the motor frame 31 is mounted in bearings 42 of the carriage 45, are a low cost feature of construction and are of great value in reducing vibration in the operation of a machine of this service. This provides, as it were, means for the parts to automatically adjust their own centers of activity wherein there is the least vibration in the operations involved.

Other inventions in relation to low cost constructions are involved in the base frame member and its mountings. The flat board base or other low cost flat base 11 with its bracket and stud mountings of the operative parts is a highly valuable construction of low cost in a machine of this class.

My vibrating armature block 115 on stylus shaft 109 is provided with electrical coils 116 and 117 through which the ends of armature block 115 enter and extend through the central region of these coils. The stylus shaft 109 on which armature block 115 is mounted passes between the coils. This arrangement provides a balancing effect on each side of the stylus shaft 109 which is a great desideratum in the operation of the armature block 115. The resilient tips of screws 123 substantially dampen the vibration in contacting the armature block 115, and by limiting the movement of the armature block ends the result is obtained, as it were, to help overcome the inertia of the return stroke or return vibration in the opposite direction. I compare the feature of saving inertia loss to what occurs in handling a hammer successively when pounding on anything that results in a rebound of the hammer at once after the contact. The old saying being, catch your hammer on the up stroke with the rebound, thus conserving the inertia of the movement. However quickly the armature block may respond to the magnetic impulses there is inertia from the reverse movement and these resilient tip contacts are the most efficient and least objectionable of any feature of this kind I have yet discovered.

The special arrangement of coils 116 and 117 in arrangement with the magnets as shown is highly efficient and of low cost construction.

The adjustable bearings 118 for the stylus shaft 109 allows the stylus shaft 109 to vibrate but not chatter in these bearings which is a great desideratum. The flat link 113 holds the stylus shaft 109 from endwise vibration and yet by its slight bending torque allows the shaft to vibrate rotarly sufficiently for the service required. This bar also acts as a sort of spring damper in either direction of the rotation of the stylus shaft.

The mechanisms herein before described result in producing a machine having special desirable new features not presently obtained by any machine in this class insofar as I am informed.

By this mechanism both the old style constant speed revolution disk records and the variable speed disk records may be cut or played back.

not only as to new records but also those that have been previously produced.

This mechanism is highly valuable in relation to recording and playing back variable speed records in a manner that much longer records may be recorded and played back on any given sized record in relation to the constant speed type of disk.

To change the operations of my mechanism from the constant speed travel of the table to that of the variable speed may be brought about by turning a single knob being that of the screw cap 16.

When the screw cap 16 is not clamped down on the disk of the turntable then the motor driving unit is adapted to drive and revolve the table at a constant rate of speed. When the screw cap is screwed down tightly clamping the disk record onto the table then the driving mechanisms for the table will revolve it at a variable speed. In either case the revolution of the table by the motor driving unit takes place only when it contacts the underside of the table and this is always the case when the front end of the rocking carriage in which the motor driving unit is carried is held upwardly by having its front end supported on either edge of the flat transverse bar 70. The movement of this bar from edge position and vice versa is brought about by revolving knob 77 in either direction. When the knob 77 is revolved to revolve the flat bar 70 to flat position this is required only at intervals of time when the motor drive is free from driving the turntable and the half nut 67 is also free from the screw threaded shaft 18.

In this situation the front end of the carriage 45 is in its lower position and thus the friction contact of the motor drive with the turntable is free from the turntable. Further when the front end of the carriage 45 is in its lower position supported on the flat side of the bar 70 its outer end 50 of the carriage 45 is lifted upwardly and this movement rocks upward the cross bar 54 on which the stylus head is supported and thereby lifts the stylus from the record. Thus the lower position of the front end of the carriage 45 is the situation for the exchange of records on the turntable as then the turntable is at rest and is also the situation for the adjustment of the stylus at any point on the record. Further this is the situation when the carriage 45 is manually moved transversely to return the carriage with its motor drive when the machine is used for variable speed driving of the turntable.

This manual operation may be made directly by the hand contacting the carriage 45 but a knob 78 is provided on a shaft 79 which is geared to move a crank arm 82 connected by a link 83 to the carriage 45 and thus by revolving the knob 78 the said carriage 45 and its connected parts may be adjusted to any position desired.

Thus the machine may be adjusted as desired for any of its uses by revolving the three knobs being the screw cap 16, knobs 77 and 78. Thus instructions for adjusting the machine need necessarily extend only beyond imparting the information as to how to turn the aforesaid three knobs.

As to the knob 77 which is geared to revolve the flat bar 70 in either direction of, the revolution of said knob 90 degrees thus bringing either edge of said flat bar to the upward position which position not only produces the contact of the motor driving unit to revolve the turntable but since one of the trunnions of the said flat bar

is connected to mechanism extending back to the rear of the machine which raises and lowers the stylus head and also switches the electric current from situations involved at one time in cutting a record and at other times in playing back a record the latter situations are controlled in the switching operations by the direction or the revolution of the knob 77 as described and shown in the specification and drawings.

Thus it is clearly shown that whatever use is made of the machine a knowledge required for operating it is required only as to an understanding of how to revolve the aforesaid three knobs. This is a great desideratum particularly so in relation to the use of the machine by blind persons and many others.

The above described knobs are located in the case of the machine above the main mechanisms thereof which permits coverage above those mechanisms leaving only the knobs, the turntable and the stylus head and its mountings about the coverage of the lower mechanisms of the machine.

In addition to the above described operative advantages of the machine the mechanical constructions generally involved in this machine provide accuracy of movement and freedom from injurious vibrating features which are serious interferences in the performances of a machine of this class. The mountings of the motor driving unit having the elastic trunnion connection which allow as it were a self centering action of the revolutions of the electric motor aid in providing a smooth operation and thereby prevent vibrations which might injure the recording and play back sound productions.

What I claim is:

1. In a machine of the class described, a turntable on which a record body is mounted, a motor driving unit contacting the under side of the turntable in driving the same, a friction wheel mounted in the said driving unit for contacting the said turntable, a rocking carriage on which said driving unit is mounted, trunnions in the said driving unit, bearings in the said carriage in which said trunnions are mounted and the said bearings located in the front portion of said rocking carriage, a transverse shaft on which said carriage is mounted, the mounting of said carriage on said transverse shaft being located near the middle length of the said carriage and in form to rock on the said shaft and to slide lengthwise on the said shaft, a base frame member on which the said transverse shaft is mounted, a transverse screw threaded shaft mounted parallel with the said transverse shaft and supported on the said base member and located below the said carriage and between the front end of said carriage and the transverse shaft on which the said carriage is mounted, a threaded half nut mounted on said carriage in position to contact the said threaded shaft as and when the front end of said carriage is rocked upwardly, the said turntable on its underside being provided with a vertical supporting shaft, supported in bearings on the base member of the machine, this shaft of the said turntable connected by gearing to the said transverse screw shaft whereby the latter may be revolved by the rotation of the said turntable, said gearing adapted to be connected and disconnected in relation to driving the said transverse screw threaded shaft whereby the latter may be revolved by the rotation of the said turntable, said

gearing adapted to be connected and disconnected in relation to driving the said transverse screw shaft by the revolution of the said turntable, a transverse bar of eccentric form located in the front region of the said rocking carriage, trunnions on the said bar being supported by bearings on the said base frame, means for revolving the said bar from a vertical raised position to a lower position in relation to the said base member, a roller mounted on the front end of the said carriage and contacting the said bar, the position of the said half nut which contacts the said transverse threaded shaft being located on the said rocking carriage whereby the front end of the said rocking carriage is supported upwardly on the edge of said bar through the means of the said roller the said half nut contacts the said transverse threaded shaft, when the front end of said rocking carriage is lowered to a position where the said roller contacts the said side of said bar then the said half nut is free of the said threaded shaft.

2. In a machine of the class described, a turntable on which the record body is mounted, a motor driving unit adapted to contact the underside of the turntable in driving the same, this motor unit provided with a friction wheel for contacting the turntable, a rocking carriage on which the said motor driving unit is mounted, the said motor unit being supported in the said rocking carriage by means of trunnions in bearings in the said rocking carriage, the location of these trunnions and bearings in the said carriage being at the front end of said carriage, the said motor unit adapted to rock slightly in relation to its position to the said rocking carriage, a spring connection from the said motor unit to the said rocking carriage adapted to hold the said motor unit in elastic rocking position as relates to motion on its trunnions supports in the said rocking carriage, a transverse supporting shaft mounted across the base member of the machine, bearings on the said rocking carriage located approximately at the middle length of the said carriage, said bearings mounted on the said transverse shaft and adapted to rock thereon and slide along the said shaft, a transverse screw threaded shaft supported in bearings from the base member of the machine and located parallel with the aforementioned transverse shaft and this location being on the side toward the front end of the said rocking carriage as relates to the said transverse supporting shaft, a threaded half nut mounted on said rocking carriage and located beneath the position of the said transverse screw threaded shaft and adapted to contact the said threaded shaft as the front end of the said rocking carriage is rocked upwardly, the said turntable provided with a vertical supporting shaft beneath the table and supported in bearings on the base member of the machine, gearing adapted to connect between the said vertical shaft of the said turntable and the said transverse screw threaded shaft, said gearing adapted to be connected and disconnected in relation to the rotation of the said screw threaded shaft by the revolution of the said turntable, a transverse flat bar provided with trunnions on its end, bearings supporting the said trunnions on the base member of the machine and this flat bar located at the front end of the machine and across and in association with the front end of the said rocking carriage and adapted to contact the front end of the said rocking carriage and raise and lower the same by means of a portion of said rocking carriage adapted to rest on the flat surface and on the edge of the said flat bar, means adapted to revolve the said bar from a flat position to a vertical edgewise position and thereby to raise and lower the front end of said rocking carriage to rock about its support on the said transverse supporting shaft and thereby raise and lower the said motor driving unit to contact the under side and revolve the said turntable and to raise and lower the said

of said rocking carriage adapted to rest on the flat surface and on the edge of the said flat bar, means adapted to revolve the said bar from a flat position to a vertical edgewise position and thereby to raise and lower the front end of said rocking carriage to rock about its support on the said transverse supporting shaft and thereby raise and lower the said motor driving unit to contact the underside and revolve the said turntable and to raise and lower the said half nut to contact and be free from the said transverse threaded shaft; in combination with means for revolving the said flat bar on its trunnions.

3. In a machine of the class described, a turntable on which the record body is mounted, a motor driving unit adapted to contact the underside of the turntable in driving the same, this motor unit provided with a friction wheel for contacting the turntable, a rocking carriage on which the said motor driving unit is mounted, the said motor driving unit being supported in the said rocking carriage by means of trunnions in bearings in the said rocking carriage, the location of these trunnions and bearings in the said carriage, the said motor unit adapted to rock slightly in relation to its position to the said rocking carriage, a spring connection from the said motor unit to the said rocking carriage adapted to hold the said motor unit in elastic rocking position as relates to motion on its trunnions supports in the said rocking carriage, a transverse supporting shaft mounted across the base member of the machine, bearings on the said rocking carriage located approximately at the middle length of the said carriage, said bearings mounted on the said transverse shaft and adapted to rock thereon and slide along the said shaft, a transverse screw threaded shaft supported in bearings from the base member of the machine and located parallel with the aforementioned transverse shaft and this location being on the side toward the front end of the said rocking carriage as relates to the said transverse supporting shaft, a threaded half nut mounted on said rocking carriage and located beneath the position of the said transverse screw threaded shaft and adapted to contact the said threaded shaft as the front end of said rocking carriage is rocked upwardly, the said turntable provided with a vertical supporting shaft beneath the table and supported in bearings on the base member of the machine, gearing adapted to connect between the said vertical shaft of the said turntable and the said transverse screw threaded shaft, said gearing adapted to be connected and disconnected in relation to the rotation of the said screw threaded shaft by the revolution of the said turntable, a transverse flat bar provided with trunnions on its end, bearings supporting the said trunnions on the base member of the machine and this flat bar located at the front end of the machine and across and in association with the front end of said rocking carriage and adapted to contact the front end of said rocking carriage and raise and lower the same by means of a portion of said rocking carriage adapted to rest on the flat surface and on the edge of the said flat bar, means adapted to revolve the said bar from a flat position to a vertical edgewise position and thereby to raise and lower the front end of said rocking carriage to rock about its support on the said transverse supporting shaft and thereby raise and lower the said motor driving unit to contact the under side and revolve the said turntable and to raise and lower the said

half nut to contact and be free from the said transverse threaded shaft, with means for revolving the said flat bar on its trunnions; in combination with a stylus head and means for supporting the same over a record position on the said turntable.

4. In a machine of the class described, a turntable on which is mounted a sound record body, a power unit adapted to revolve said turntable, a rocking carriage on which said power unit is mounted, said rocking carriage mounted on a transverse shaft supported on the base member of the machine, said rocking carriage adapted to rock on the said shaft and slide along thereon, said power unit mounted on the front end of said rocking carriage, a transverse flat bar supported in trunnions on the base member of the machine and across in front of the front end of the said rocking carriage and this end of the said carriage supported by the said flat bar, a transverse screw threaded shaft mounted across the base member of the machine in parallel relation to the said transverse shaft, means for revolving the screw threaded shaft by a revolving movement of the said turntable, this means adapted to be connected and disconnected in relation to revolving the said screw threaded shaft, a half nut connected to the said rocking carriage in position to engage the said transverse screw shaft and be actuated thereby to move the said rocking carriage when the front end of the said carriage is in its upward position and be disconnected from the said screw threaded shaft when the said front end of said carriage is in its lower position, means for revolving the said flat transverse bar from a flat position whereat it supports the front end of said carriage at its lower position whereat the said half nut is free from the said screw shaft, to its edge position whereat the front end of said carriage is in its upward position at which the said half nut is contacted by the said screw threaded shaft.

5. In a machine of the class described, a turntable on which is mounted a sound record body, a power unit adapted to revolve said turntable, a rocking carriage on which said power unit is mounted, said rocking carriage mounted on a transverse shaft supported on the base member of the machine, said rocking carriage adapted to rock on the said shaft and slide along thereon, said power unit mounted on the front end of said rocking carriage, a transverse flat bar supported by trunnions on the base member of the machine and across and in front of the front end of the said rocking carriage and this end of the said carriage supported by the said flat bar, a transverse screw threaded shaft mounted across the base member of the machine in parallel relation to the said transverse shaft, means for revolving the screw threaded shaft by a revolving movement of said turntable, this means adapted to be connected and disconnected in relation to revolving the said screw threaded shaft, a half nut connected to the said rocking carriage in position to engage the said transverse screw shaft and be actuated thereby to move the said rocking carriage when the front end of the said carriage is in its upward position and be disconnected from the said screw threaded shaft when the said front end of said carriage is in its lower position, a means for revolving the said flat

transverse bar from a flat position whereat it supports the front end of said carriage at its lower position whereat the said half nut is free from the said screw shaft, to its edge position whereat the front end of said carriage is in its upward position at which the said half nut is contacted by the said screw shaft, gearing connected to one of the said trunnions of the said flat bar whereby the said bar may be revolved from flat to vertical edge positions.

6. In a machine of the class described, a turntable on which is mounted a sound record body, a power unit adapted to revolve said turntable, a rocking carriage on which said power unit is mounted, said rocking carriage mounted on a transverse shaft supported on the base member of the machine, said rocking carriage adapted to rock on the said shaft and slide transversely along thereon, said power unit mounted on the front end of said rocking carriage, a transverse flat bar supported in trunnions on the base member of the machine and across in front of the front end of the said rocking carriage supported by the said flat bar, a transverse screw threaded shaft mounted across the base member of the machine in parallel relation to the said transverse shaft, means for revolving the screw threaded shaft by a revolving movement of said turntable, this means adapted to be connected and disconnected in relation to revolving the said screw threaded shaft, a half nut connected to the said rocking carriage in position to engage the said transverse screw shaft and be actuated thereby to move the said rocking carriage when the front end of the said carriage is in its upward position and be disconnected from the said screw threaded shaft when the said front end of said carriage is in its lower position, means for revolving the said flat transverse bar from a flat position whereat it supports the front end of said carriage at its lower position whereat the said half nut is free from the said screw shaft to its edge position whereat the front end of said carriage is in its upward position at which said half nut is contacted by the said screw shaft, gearing connected to one of the said trunnions of the said flat bar whereby the said bar may be revolved from flat to vertical positions; in combination with a rear transverse shaft mounted across the rear of the base frame member, a rocking sliding block on said rear transverse shaft, said block connected to the rear end of said rocking carriage in a manner to be moved transversely of the base member as and with the said rocking carriage when it is moved transversely, a stylus head supporting by the said rocking sliding block, a counterbalancing spring fixed on said rocking sliding block, a transverse crank rod mounted parallel in relation to said rear transverse shaft and in contact with said counterbalancing spring, a crank arm on said crank rod, said arm connected by a connecting rod to a crank lever fixed on one of the trunnion ends of said transverse flat bar whereby the revolving of the said bar acts to move the said crank rod upward or downward in contact with the said counterbalancing spring thus becoming a counterbalance in relation to the support of the said stylus head over a record body on said turntable.

EDWARD ROBERT HARRIS.
